(No Model.)

J. B. WOOD.
FOLDING CAR GATE.

No. 601,610.

Patented Mar. 29, 1898.

UNITED STATES PATENT OFFICE.

JOHN B. WOOD, OF OAK LAWN, RHODE ISLAND.

FOLDING CAR-GATE.

SPECIFICATION forming part of Letters Patent No. 601,610, dated March 29, 1898.

Application filed May 1, 1897. Serial No. 634,775. (No model.)

To all whom it may concern:

Be it known that I, JOHN B. WOOD, a citizen of the United States, residing at Oak Lawn, in the State of Rhode Island, have invented a new and useful Improvement in Folding Car-Gates, of which the following is a specification.

The object of my invention is to provide a car-gate which is adapted to fold into a small compass when not in use; and it consists in the improved construction of the folding gate and in the means for locking the same, as hereinafter fully set forth.

In the accompanying drawings, Figure 1 represents a detail top view of the platform of a car, showing the gate in its closed condition. Fig. 2 represents the same with the gate in its opened condition and folded at the end of the car. Fig. 3 represents the side view of the gate when in its closed condition. Fig. 4 represents an enlarged detail view broken away to show the locked condition of the upper joint between the folding parts of the gate. Fig. 5 represents a similar view showing the unlocked condition of the upper joint. Fig. 6 represents a view of the upper joint, showing a section taken on the line 6 6 of Fig. 5 when the hinged parts of the gate are turned at a right angle to each other. Fig. 7 represents a view of the upper joint when the hinged parts of the gate are in their folded condition. Fig. 8 is a detail sectional view on the line 8 8 of Fig. 7, showing the locked condition of the joint when the parts of the gate are in their folded condition. Fig. 9 is a sectional view showing a modification in the locking means. Fig. 10 represents a section taken on the line 10 10 of Fig. 9, showing the position of the disengaging cam in the locked closed position of the gate. Fig. 11 is a similar section showing the position of the cam in the folded position of the gate.

In the drawings, A represents the platform of the car; B, the steps; C, the end wall of the car, and D the car-door. The gate E is made in two parts a and b, which are hinged to each other at the joints c and d, so that the said two parts may be folded together, as shown in Fig. 2. The pivot-rod e of the gate-sections a and b passes loosely through suitable perforations made in the ears f f' of the upper joint and the corresponding ears g g'

of the lower joint, the said ears f f' being provided with the perforations h h and h' h', made to come in line with each other both 55 when the gate is closed, as shown in Fig. 1, and when in its open and folded condition, as shown in Fig. 2, the said perforations h h and h' h' being made at equal distances from the axis of the pivot-rod e, the said pivot-rod 60 being provided with the handle i and the locking-pins j j, which are held in the perforations h h of the ear f of the outer portion a of the gate and adapted to enter the perforations h' h' of the ear f' of the inner portion b of the 65 gate, thus serving to lock the two parts of the gate in either the opened or the closed position of the same, the said locking-pins j j being held in engagement with the perforations h' h' of the ear f' by means of the spiral spring 70 k, which, by acting against the pin l of the pivot-rod e, serves to cause the forcible downward movement of the said locking-pins j j, the locked condition of the joint for the closed position of the gate being shown in Fig. 4 and 75 for the open and folded condition of the gate in Figs. 7 and 8.

The inner portion b of the gate is jointed to the pintles m m, secured to the end wall of the car, and to the bearing-brackets n n', which 80 project from the corner of the car, is pivoted the swinging arm F, the said swinging arm being jointed at the point o to the top of the outer portion a of the gate, so that when the gate is closed, as shown in Fig. 1, the arm F 85 will form a brace for the gate against outward movement and will fold inward to the position shown in Fig. 2 upon opening the gate, and at its opened, folded, and locked condition, as shown in Fig. 2, the lower end 90 of the pivot-rod e will be caught and retained by the catch p, arranged upon the platform A of the car, so that upon the unlocking of the joint by raising the rod e against the downward action of the spring k the gate may be 95 readily opened out to its closed position, as shown in Fig. 1.

A modification of the locking means for the joint of the gate-sections is shown in Fig. 9, in which the pivot-rod e of the joint is adapted 100 for turning movement instead of a sliding movement, and a locking-spring t is arranged upon the side of the section b of the gate, the said locking-spring being provided with the

spur *u*, which is adapted to engage with the notch *v* to lock the joint of the gate in its opened position and with the opposite notch *v'* to lock the gate in its folded position, the 5 said notches being made at opposite sides of the ear *f* of the section *a* of the gate. The pivot-rod *e* is adapted for partial rotation in the ear *f* of the outer portion *a* of the gate and is provided with the attached cam *w*, having the notch *w'*, and with the operating-handle *i*. Upon the initial movement of the pivot-rod *e* by means of the handle *i* the action of the cam *w* upon the end of the locking-spring *t* will serve to cause the disengagement of the 15 said spring from the locking-notch *v* or *v'*, as the case may be, after which the engagement of the side of the notch *w'* with the pin *x*, attached to the ear *f* of the outer portion *a* of the gate, will serve to cause the proper opening or closing movement.

I claim as my invention—

1. In a folding car-gate, the combination of the folding gate-sections, with the swinging rod or brace which controls the folding movement, and means for locking the folding joint of the gate, substantially as described.
2. In a folding car-gate, the combination of

the folding gate-sections, with the sliding pivot-rod adapted to lock the gate at the folding joint, substantially as described.

3. In a folding car-gate, the combination of the folding gate-sections, with the swinging rod which controls the folding movement, the sliding pivot-rod, and the catch for the lower end of the pivot-rod for holding the gate in 35 its folded condition at the end of the car, substantially as described.

4. In a folding car-gate, the combination of the folding gate-sections, provided with the locking perforations, with the sliding pivot-rod provided with the locking-pins, substantially as described.

5. In a folding car-gate, the combination of the folding gate-sections having the locking perforations made in their joint-ears, with the 45 sliding pivot-rod provided with the locking-pins adapted to enter the locking perforations of the gate-sections, and the spring for holding the pivot-rod in locking engagement, substantially as described.

JOHN B. WOOD.
